(No. Model.)

A. FERRON.

MACHINE FOR CRUSHING AND DISINTEGRATING SUGAR CANE.

No. 279,235.

Patented June 12, 1883.

UNITED STATES PATENT OFFICE.

ALEXANDRE FERRON, OF PARIS, FRANCE, ASSIGNOR TO HIMSELF AND SOCIÉTÉ ANONYME DES ANCIENS ETABLISSEMENTS CAIL, OF SAME PLACE.

MACHINE FOR CRUSHING AND DISINTEGRATING SUGAR-CANE.

SPECIFICATION forming part of Letters Patent No. 279,235, dated June 12, 1883.

Application filed March 10, 1883. (No model.) Patented in France September 19, 1881, No. 144,909.

To all whom it may concern:

Be it known that I, ALEXANDRE FERRON, of Paris, in the Republic of France, have invented a new and useful Machine for Crushing and Disintegrating Sugar-Cane; and I do hereby declare that the following is a full, clear, and exact description of the same.

My invention consists in a new crushing and disintegrating machine for sugar-cane, intended to be placed in front of the cane-mill in such manner that the cane is compelled to pass through it before arriving between the rollers of the mill. This apparatus, composed of two rotary cylinders with sharp-edged helicoidal flutings, receives the whole length of the cane in a direction normal to the straight generatrices of the cylinders, which, by their rotary movement, crush in some degree, and at the same time split, the cane throughout the whole length, and in a direction presenting the form of a helix more or less elongated, according to the differences of the speeds of rotation of the cylinders. By thus reducing the cane the motive power necessary for crushing it in the mill will be considerably diminished, at the same time that the extraction of the juice will be facilitated and the product will be increased.

Figure 1 in the drawings is a side elevation of the apparatus. Fig. 2 is a plan. Fig. 3 is a front elevation. Figs. 4 and 5 represent in axial profile, on a larger scale, the form and arrangement of the threads or flutings of the two cylinders.

Similar letters of reference indicate like parts.

The apparatus is composed, essentially, of two cylinders, C C', of cast-iron, bronze, or cast-steel, which preferably have the same length as that of the crushing-rollers of the mill with which the apparatus is intended to operate. These cylinders, which are parallel with each other and at a short distance apart, are threaded or fluted throughout their whole length, the threads or flutes presenting the forms and arrangements represented full size, Figs. 4 and 5. It will be seen by reference to the latter figures that the rectangular triangular sectional forms of these threads or flutings are arranged in contrary directions on the two cylinders in such

manner that by the rotation of the cylinders 50 these threads or flutings present a series of sharp-edged helicoidal blades, which will have a somewhat shearing operation, by which operation the canes passing between the cylinders will be split throughout their whole length in 55 straight or helical directions, according as the speeds of rotation of the two cylinders are equal or unequal. In the example represented in the drawings the cylinders C C' are furnished on half their length with a series of threads 60 or spiral fillets having a right-hand pitch, and on the other half with a series of threads or fillets having a left-hand pitch. These two series are separated by a groove intended to receive a separating-partition, which keeps 65 the sugar-canies upon the proper helicoidal threads or flutings of the apparatus. The right or left hand threads of each cylinder are opposite corresponding threads on the other cylinder. 70

The cylinders C are furnished at their extremities with journals turning in boxes in the side frame, A, and are geared together by pinions P P, which may be of equal or different diameters, according to the angle at which the 75 canes are desired to be split by the cutting-edges of the threads or flutings of the cylinders.

One of the cylinders is furnished with a large spur-wheel, B, gearing with a smaller spur 80 wheel or pinion, D, on the shaft E of the motor.

In front of the machine is arranged an endless-chain cane-feeder, F, (like those commonly employed in a sugar-mill,) for feeding the cane to the cylinders C C', which are represented in 85 the drawings as arranged in front of the ordinary sugar-mill, H, between which and the said cylinders is arranged an inclined plane, G, along which the cane, after having been split and disintegrated by the said cylinders, passes 90 to the mill.

I am aware of British Letters Patent No. 8,731, dated December 2, 1840, and I do not claim anything shown therein as of my invention. Said Letters Patent show cylinders between which the cane passes on its way to the cane-mill, and which have spiral grooves, like screw-threads, for the purpose of spreading the 95

cane laterally before it enters the mill, and thereby presenting it uniformly to the crushing-rollers throughout their length. Said Letters Patent also describe a table having diverging grooves or gutters which aid in spreading the cane; and it is also described that such a grooved or guttered table may be used with plain-surfaced rollers or cylinders. The function of the cylinders in said Letters Patent is not to split the cane, and it is not stated therein that they accomplish such a purpose. My screw-threads are sharp-edged, so that they have a shearing action upon the cane and split it lengthwise. Their function is not to spread the cane laterally. In the apparatus shown in the aforesaid Letters Patent, if the right or left hand grooves of each cylinder were opposite corresponding grooves in the other cylinder, as described by me, and if the cylinders were then rotated in opposite directions, the cylinders would not have the spreading action described in the aforesaid Letters Patent.

What I claim as my invention is—

1. The combination, in a machine for preparing sugar-cane for the cane-mill, of two cylinders, between which the cane passes be-

fore it reaches the cane-mill, and which are provided with helicoidal sharp-edged threads, which operate on the cane with a shearing action, thereby splitting it lengthwise, and to some extent crushing it before it enters the cane-mill, substantially as herein described.

2. The combination, in a machine for preparing sugar-cane for the cane-mill, of two cylinders geared to rotate in opposite directions, between which the cane passes before it reaches the cane-mill, and which are provided with helicoidal sharp-edged threads, which operate upon the cane with a shearing action, thereby splitting it throughout its length, and to some extent crushing it before it enters the cane-mill, the right or left hand threads of each cylinder being opposite corresponding threads on the other cylinder, substantially as and for the purpose herein described.

This specification signed this 24th day of January, 1883.

ALEXANDRE FERRON.
